[Term of Patent 3½ years]

CASE F.

To all whom it may concern:

Be it known that I, EMIL CRISAND, of New Haven, in the county of New Haven and State of Connecticut, have invented a new Design for Embroidery-Pattern; and I do hereby declare the following, when taken in connection with the accompanying drawings and the letters of reference marked thereon, to be a full, clear, and exact description of the same, and which said drawings constitute part of this specification, and represent the design.

This invention relates to a design for embroidery-pattern, intended especially for perforated board; and it consists in the peculiar configuration and ornamentation of the motto, as shown in the accompanying illustration.

The motto forming the base of the design is "Simply to Thy Cross I Cling," the cross being illustrated by the figure of a cross. The

form of the letters composing the several words is clearly shown in the accompanying illustration, the capitals being the principal features in this part of the design.

The ornamentation of this design consists of a tracery of a floriated character, interwoven with the words and the figure of the cross, as clearly shown in the accompanying illustration.

I claim—

The design for embroidery-patterns herein described, consisting of the motto "Simply to Thy Cross I Cling," in form and ornamentation as shown in the accompanying illustration.

EMIL CRISAND.
